UNITED STATES PATENT OFFICE.

GEORGE W. BEADLE, OF BAYONNE, NEW JERSEY, ASSIGNOR TO SINGLE SERVICE PACKAGE CORPORATION OF AMERICA, OF NEW YORK, N. Y., A CORPORATION OF NEW JERSEY.

MACHINE FOR MAKING CARTON-BODIES.

1,133,913.

Specification of Letters Patent. Patented Mar. 30, 1915.

Application filed March 20, 1912, Serial No. 685,075. Renewed August 1, 1914. Serial No. 854,561.

To all whom it may concern:

Be it known that I, GEORGE W. BEADLE, a citizen of the United States, residing at Bayonne, in the county of Hudson and State 5 of New Jersey, have invented certain new and useful Improvements in Machines for Making Carton-Bodies; and I do hereby declare the following to be a full, clear, and exact description of the invention, such as 10 will enable others skilled in the art to which it appertains to make and use the same.

This invention relates to machines for forming carton bodies, and has for its object to produce a mechanism which will 15 readily reduce the diameter of spirally wound tubes at predetermined positions in their length, and thereupon sever such tubes at the reduced portions to form carton bodies having reduced ends over which cap 20 closures may be slipped.

The invention consists in the novel details of construction and combinations of parts more fully hereinafter described and particularly pointed out in the claims.

25 Referring to the accompanying drawings forming a part of this specification in which like numerals designate like parts in all the views:—Figure 1 is a side elevational view of a machine made in accordance with my 30 invention, with certain parts omitted for the sake of clearness; Fig. 2 is an end elevational view of the machine including the parts omitted from Fig. 1; Fig. 3 is a cross sectional view of a portion of the parts 35 shown in Fig. 1; Fig. 4 is an elevational view of a portion of the mandrel and showing the tube thereon in sectional view; Fig. 5 is a perspective view of a carton body made by this machine.

40 1 indicates any suitable supports or legs for the machine proper; 2 the bed of the machine; 3 a standard or bracket rising from the bed 2; 4 a second standard also rising from said bed; 5 an additional standard; and 6 still another standard pivoted 45 as at 7 to a bracket 8, and provided with a bell-crank extension 9.

Passing through the standard 3 is one end of the mandrel 10 on which is also secured a pulley 11, and said mandrel is provided at its 50 other end with a reduced portion 12 fitting a hole 13 in the hinged standard 6, as shown. The said hinged standard is connected as at 14 with the one end of the rod 15 whose other 55 end is at 16 connected with one arm 17 of

the bell-crank lever pivoted as at 18 to the bed 2, and having another arm 19 to which is pivoted as at 20, a rod 21, to which is attached as at 22 a foot lever 23, pivoted to the rod 24 secured to the supports 1.

A spring 25 normally keeps the foot lever 23 in its raised position, and when the said lever is depressed, the pivoted standard 6 is forced from its full line position shown in Fig. 1, into its dotted line position in 65 engagement with the end 12 of the mandrel, as will be readily understood.

A shaft rod 30 is journaled in the standards 4 and 5, and has secured thereto the pressure shoes 31 having the curved circular 70 shaped surfaces 32 adapted to contact with the paper tube 33 surrounding the mandrel 10, and to reduce the diameter of the same by pressure against said mandrel in the places 34, as shown. That is to say, the said 75 tube 33 loosely fits the mandrel 10 (see Fig. 3) and the said mandrel is preferably provided with the depressions or grooves 36 into which the material of the paper may be forced by the curved surfaces 32 to form 80 the depressions 34, as clearly illustrated in Fig. 4. Said depressions formed in the tube are, however, not of sufficient depth to prevent the removal of the tube from the mandrel.

In order that the shoes 31 may more effectually perform their work, gas jets 37 are provided for heating the same. These jets are connected by the tubes 38 to the gas supply pipe 39. The several shoes 31 are 90 moved into and out of engagement with the tube on the mandrel by the handle lever 40 that is pivoted to the stud 41 on the standard 5 (see Figs. 1 and 3), and is provided with a slotted arm 42 which engages the pin 95 43 carried by the arm 44, that is rigid with the shaft 30, as best shown in Fig. 3.

It is evident that when the lever 40 is depressed, its rigid extension 42 will be swung in a clockwise direction, (see Fig. 3) 100 and carries with it the pin 43 and the lever 44, which latter being rigid with the shoe 31, will swing said shoe in a counter-clockwise direction, or against the carton 33, and force the material of the same into the 105 grooves 36 on the mandrel 10.

The mandrel 10 being revolved through the pulley 11, and the shoes 31 being heated by the jets 37, the paper is permanently set in the said grooves 36, and therefore the 110

finished tube presents the appearance best illustrated in Fig. 4. The whole operation is quite rapid and efficient.

While the tube is being grooved by the heated shoes, the knives or disks 50 are brought into contact with the depressed portions 34, and sever the same along the lines 51, as best indicated in Fig. 4. Each of these knives is preferably in the form of a disk, as shown, and is carried in a bracket 52, (see Fig. 2) and adjustable by means of the screw 53. A cutter support or bracket similar to that shown in Fig. 2 is provided at or near the free end of the mandrel.

The several brackets 52 are adjustable to and from the carton 33 by means of the screws 54 passing through the bearings 55 rigid with the brackets 56 mounted on the bed 2 of the machine. The said screws 54 constitute the supports for the pivots 56' of the bars 57 on which bar said brackets and knives are mounted, and said bar is provided with an arm or extension 57' having pivoted, as at 58, the rod 59 that is connected at 60 with the foot lever 23.

It will now be clear that as the foot lever 23 is depressed, it will pull down on the rod 59, and will cause the bar 57 to swing on the pivots 56', and to thereupon force the knives 50 into contact with the carton 33. In the meantime, it will also be clear that the pivots 56' can be bodily shifted to and from the carton tube 33 by moving the nuts 61 surrounding said screws 54. It will further be clear that upon adjusting the screw 53, the knife disks 50 can be moved to and from the said carton 33 in a vertical plane, and that in such movement the supports 62 of said knives will swing on the pivots 63 carried by the brackets 52.

The spring 25 normally returns the foot lever 23 to its uppermost position, as will be clear from the drawings.

The operation of my invention will be clear from the foregoing, but may be briefly summarized as follows:—A tube of uniform diameter and preferably of a spirally wound character, is slipped over the mandrel 10, provided with the grooves 36, which mandrel is of a diameter somewhat less than that of the tube, as shown. The pivoted bracket 6 is next swung into its dotted line position, as shown in Fig. 1, by a depression of the foot lever 23. Power being continuously applied to the pulley 11, the said mandrel is rapidly rotated, and upon a depression of the hand lever 40, the compressing shoes 31 are brought into contact with the tube 33 and force the material of the same into the tapered grooves 36, as illustrated. The gas jets 37 maintain the shoes 31 at a sufficiently high temperature to rapidly and permanently set the material of the tube, and therefore, to form it into the shape shown in Fig. 4. On the same depression of

the foot lever 23, the knives 50 are brought into contact with the said tube at the depressed portions 34, and sever the said tube along the dotted lines 51 into suitable lengths for making carton bodies 70, as illustrated in Fig. 5. The said tube 33 being of a greater diameter than the mandrel 10, these carton bodies 70 are readily slipped off the said mandrel, and are supplied with suitable closures, not shown. The removal of the said bodies from the mandrel is facilitated by the fact that the spring 25 automatically raises the foot lever 23 as soon as pressure is removed therefrom, and thereupon, forces the pivoted supporting bracket 80 into its full line position shown in Fig. 1, and leaves the end of the mandrel 10 clear.

It is obvious that those skilled in the art may vary the details of construction as well as the arrangement of parts without departing from the spirit of my invention, and therefore, I do not wish to be limited to the above disclosures except as may be required by the claims.

I claim:

1. In a machine for grooving a formed tubular body intermediate its ends, the combination of a rotatable mandrel having an annular groove intermediate its ends and adapted to have the tube loosely fitted thereon; and a shoe adapted to press a portion of the tubular body into said mandrel groove, substantially as described.

2. In a machine for making carton bodies, the combination of a mandrel provided with a plurality of transverse grooves along its length over which a tube may be placed; means for rotating said mandrel; a shoe for each groove adapted to press the material of said tube into its corresponding groove during the rotation of said mandrel and thereby reduce the diameter of said tube opposite each groove; means for heating said shoes during the reducing operation; and means for severing said tube at its reduced portions, substantially as described.

3. In a machine for making carton bodies, the combination of a mandrel provided with a plurality of transverse grooves along its length over one end of which a tube is adapted to be placed; swinging supporting means to engage and disengage one end of said mandrel; means for rotating said mandrel; a curved shoe for each groove adapted to press the material of the tube into its corresponding groove and thereby reduce the diameter of the tube opposite each groove; a swinging cutter opposite each groove; means for causing said cutters to sever said tube at the reduced portions; and connections between said cutter operating means and said swinging supporting means, substantially as described.

4. In a machine for making carton bodies, the combination of a mandrel provided with

a plurality of transverse grooves having rounded corners; a swinging support adapted to engage one end of said mandrel, and to disengage said end to permit a tube to be slipped over said mandrel and grooves; means for continuously rotating said mandrel; pivoted shoes adapted to force the material of said tube into said grooves; a hand lever and connections for operating said shoes; a foot lever and connections for operating said swinging support; pivoted cutting means for severing said tube at its reduced portions; and connections between said foot lever and said cutting means, substantially as described.

5. The combination with a machine for forming a groove in a tubular body, of a device for severing the tube at the grooved portion comprising a cutting member, a support on which said cutter is swingingly mounted, a bracket on which said support is journaled, means on which said bracket is adjustably mounted, and means for swinging said bracket to bring said cutter into 20 and out of operative position, substantially as described.

6. The combination with a machine for forming an annular groove in a tubular body, of a device for severing the tube at 25

the grooved portion comprising a cutting disk, a bracket, an arm pivotally mounted on said bracket and on which said disk is mounted, a bar on which said bracket is secured, screws adjustably mounted on the frame of the machine, said bar being journaled on said screws, and manually actuated means for rotating said bar to move said bracket and bring the cutting disk into and out of operative position, substantially as described.

7. In a machine for grooving a tubular body intermediate its ends, the combination of a rotatable mandrel grooved intermediate its ends and adapted to have a tube loosely fitted thereon; a pivotally mounted 45 shoe having a curved surface adapted to embrace and press a portion of the tubular body into said mandrel groove; and a gas jet mounted on said shoe and adapted to direct its flame onto said shoe for heating said 50 curved surface, substantially as described.

In testimony whereof, I affix my signature, in presence of two witnesses.

GEORGE W. BEADLE.
